(57) **CLAIM**

The ornamental design for a LED projection light, as shown and described.

DESCRIPTION

FIG. 1 is a front, bottom perspective view of a LED projection light, showing my new design;

FIG. 2 is a rear, top perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof;

FIG. 8 is a bottom plan view thereof;

FIG. 9 is an enlarged view of the area illustrating in greater detail the ornamental feature shown in FIG. 1; and,
FIG. 10 is an enlarged view of the area illustrating in greater detail the ornamental feature shown in FIG. 2.

The dashed lines in the figures illustrate portions of the LED projection light that form no part of the claimed design.

The dot-dash-dot broken lines of the LED projection light in FIG. 1 illustrate a boundary and cut line of the enlarged view in FIG. 9 and form no part of the claimed design.

The dot-dash-dot broken lines of the LED projection light in FIG. 2 illustrate a boundary and cut line of the enlarged view in FIG. 10 and form no part of the claimed design.
